C. E. TAYLOR

APPARATUS FOR THE CLEANING OF CLOTHES AND THE LIKE

Filed Oct. 29, 1921

Patented Mar. 18, 1924.

1,487,619

UNITED STATES PATENT OFFICE.

CHARLES EDWIN TAYLOR, OF ROCKSPRINGS, TEXAS.

APPARATUS FOR THE CLEANING OF CLOTHES AND THE LIKE.

Application filed October 29, 1921. Serial No. 511,271.

To all whom it may concern:

Be it known that I, CHARLES EDWIN TAYLOR, a citizen of the United States, and a resident of Rocksprings, in the county of 5 Edwards and State of Texas, have invented certain new and useful Improvements in Apparatus for the Cleaning of Clothes, and the like, of which the following is a specification.

10 My invention consists of an improved method and apparatus of the type more particularly adapted for the cleaning of clothing, dishes, etc.

An important object of the invention is 15 to provide a device of the above named character which is so constructed that a complete circulation of the washing fluid will at all times be assured.

Another object of my invention is to produce 20 a washing machine which will be extremely simple of construction and inexpensive to operate.

Other objects and advantages of my invention reside in the novel construction, 25 combination and arrangement of parts which will be hereinafter more fully described and claimed, reference being had to the accompanying drawings, in which,

Figure 1 is a vertical section of the 30 device, and

Figure 2 is a top plan view of the same.

In the drawings a base 1 having a supporting flange 2, supports a body 3 which rises to a convenient height as shown. The bottom 4 of the body is provided with a central socket 5 on its upper side.

A holder 6 for the articles to be washed and which for convenience of reference I shall refer to as the clothes or dish holder, 40 is concentrically spaced within and from the body by means of a double series of upper and lower lugs 7 projecting radially from the holder. The bottom 8 of the holder 6 converges downwardly forming a 45 cone-shaped bottom for said container, which also serves as a chute or funnel for guiding the water or washing fluid to an outlet 9 at the center. A perforated diaphragm or plate 10 is secured near the bottom 50 of the inner container and acts as a support for the articles to be cleansed. The perforations permit circulation of the water through the holder.

A double baffle is formed of two cone-shaped sections placed one above the other as shown at 11 and 12, the lower one being

inverted and seated within the socket 5. A series of supporting brackets 13 are riveted to the upper cone section at one end and to the under side of the converging bottom 60 8, as shown, thus maintaining the double baffle and the holder in spaced relation to each other.

Thus it will be seen that this double baffle functions in such a manner that the 65 upper section 11 will tend to guide the downward flow of the relatively cooled fluid as it passes from the opening 9 toward the side and bottom walls at the lower part of the container 3. It will also be apparent 70 that the relatively hot fluid in the bottom 4 of the container 3 will tend to rise, it being displaced by the cooler portion of the fluid, but in rising will be deflected by the lower cone section 12 and the converging 75 bottom 8, and will follow the course of circulation upwardly between the walls 3 and 6. The double baffle thus permits of a means for maintaining a perfect circulation for the fluid and prevents the relatively 80 hot fluid from entering the opening 9 in its upward course.

The holder 6 is provided at its top with a downwardly dished cover 14 which converges downwardly toward its center to the 85 opening 15. The walls of the cover 14 project over the side walls of the holder so as to form a smooth run-way for the washing fluid as it passes over the same. Handles 16 and 17 are provided for lifting the cover 90 from the holder for the purpose of cleaning the inside of the same.

It should be noted that with this novel construction the holder can be entirely removed from the body for the purposes of 95 cleaning and repairing. It should also be noted that a complete circulation of the washing fluid is at all times assured.

In use the cover 14 being removed, the articles to be cleaned are deposited in the 100 holder 6 and the cover is then replaced. The base 1 being placed in position over a source of heat such as a coal range, gas burner, or any other source of heat, the heat acts directly on the water at the bottom of the body, the water rising in temperature 105 travels upwardly against the walls of the lower cone-shaped section 12 thence upwardly against the downwardly converging bottom 8 of the holder 6 and on up over the top of the cover 14 when it then assumes a downward course and is deposited into 110

the holder 6. The water then passes through the clothing or around the dishes within the holder, the force of the circulation increasing the friction of the water against or through the articles in the holder thus aiding in cleansing the same. The water then passes downwardly through the perforations in the plate 10 and against the walls of the upper cone section 11 and is deposited into the body where it is again heated to a higher temperature and commences its travel once more, thus repeating the cycle of operation many times. It will be noted in the operation of this device bubbles do not form on the inside of the holder, but are deposited on the outside of the holder. The bubbles strike the double baffle cone at the bottom of the holder and pass by the opening, in the bottom of the holder and by use of this double baffle cone the bubbles are forced on the outside of the holder.

It should be noted that I have also defined a method or process of cleaning which has been described above.

Although I have herein shown and described only one form of washing machine, it is to be understood that various changes and modifications may be made herein without departing from the spirit of the invention or the spirit and scope of the appended claims. The intention being to use this principle in washing any and all things that are to be cleaned by means of boiling water and soap.

35 What I claim is:

1. A washing apparatus substantially as described comprising a body portion, a holder therein, upper and lower series of lugs secured to said holder and projecting outwardly therefrom and securing the holder in spaced relation to the body, the said body having at its bottom a central socket, a downwardly turned top for the holder, and said top having a central opening communicating with the interior of the holder and the latter having a bottom sloping toward its center and having an opening at the center, a perforated diaphragm in the

holder above the central bottom opening, and a baffle below the holder and having an upper tapering portion projecting at its center into the central opening of the holder and a lower tapering portion seated at its center in the socket at the bottom of the body, and spaced lugs securing the baffle to the bottom of the holder, all as and for the purposes set forth.

2. In a device of the character described, a body having a socket formed on its bottom, a holder secured in spaced relation to the body, and a baffle arranged in spaced relation below the center of the holder and seated within the said socket.

3. In a device of the character described, a body, a removable holder rising to a height less than that attained by the body, a perforated supporting plate carried within the holder, and supporting means for the holder including a double baffle secured in spaced relation thereto.

4. In a device of the character described, a body, a holder, and supporting means for the holder including a sectional baffle and brackets secured to the upper section of said baffle and the bottom of the holder for maintaining the same in spaced relation, and a socket secured to the bottom of the body and adapted to receive a portion of the lower section of the baffle.

5. A washing apparatus comprising a body portion, a holder therein having a bottom provided with an opening and a baffle below the holder and having an upper tapering portion projecting at its center into the opening of the bottom of the holder, and a lower tapering portion extending downwardly from the holder.

6. A washing apparatus comprising a body portion, a holder therein having a bottom provided with an opening, a downwardly turned top for the holder having a central opening, and a baffle below the holder and having an upper tapering portion and a lower tapering portion.

CHARLES EDWIN TAYLOR.
